CLAIM

The ornamental design for a football fan's novelty hat, as shown and described.

DESCRIPTION

FIG. 1 is a front perspective view of a football fan's novelty hat showing my new design;

FIG. 2 is a front elevational view thereof, the rear view being a mirror image;

FIG. 3 is an end elevational view thereof, the opposite end being identical;

FIG. 4 is a bottom plan view thereof;

FIG. 5 is a top plan view thereof; and

FIG. 6 is a front perspective view thereof in an open position.
